CLAIM

The ornamental design for a front cover portion of operation tower of work vehicle, as shown and described.

DESCRIPTION

1. Front cover portion of operation tower of work vehicle

1.1 : Front

1.2 : Back

1.3 : Left

1.4 : Right

1.5 : Top

1.6 : Perspective

1.7 : Enlarged

1.8 : Enlarged

A bottom view is omitted because the article is heavy; the broken lines shown in the reproductions 1.1-1.8 form no part of the claimed design.

1 Claim, 8 Drawing Sheets
